INVENTOR
Henry W. Antholz.
BY *Henry W. Antholz*
ATTORNEY

UNITED STATES PATENT OFFICE.

HENRY W. ANTHOLZ, OF McDONALD, KANSAS.

MAIL CARRIER.

1,404,679.

Specification of Letters Patent. Patented Jan. 24, 1922.

Application filed February 14, 1921. Serial No. 444,732.

To all whom it may concern:

Be it known that I, HENRY W. ANTHOLZ, a citizen of the United States, residing at McDonald, in the county of Rollins and

5 State of Kansas, have invented certain new and useful Improvements in Mail Carriers; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to aerial railways in which a superposed track supports a car or cars adapted to carry merchandise, mail and the like.

The invention is particularly applicable 20 for use in connection with rural free delivery routes in which a circuitous track is provided, over which may travel one or more cars from a central station, to be returned to the central station after making the circuit.

25 At suitable intervals in the circuit will be provided stations representing the points of delivery and collection, it being possible to automatically release a car at a designated point and pick up another car or proceed without picking up another car until another station has been reached, whereupon a second car may be automatically detached until all the cars in the train have been released. The number of cars in the train 30 propelled by the motor car or pilot car will depend upon the number of stations in the circuit and certain mechanism on each drawn car can be set to cause that particular car 35 to be released at a particular station.

The specific details of construction embodied in the preferred form of my invention will be described hereinafter, it being understood that changes in form, proportion 40 and minor details of construction may be resorted to without departing from the spirit of the invention or sacrificing any of its advantages.

In the drawings,

50 Fig. 1 is a perspective view of a pilot car and one trailer, part of the trailer being broken away to show the setting mechanism therein.

Fig. 2 is a vertical, longitudinal, sectional view through the pilot car and one trailer.

55

Fig. 3 is a detail perspective view of the coupling release, and

Fig. 4 is a side elevational view on a reduced scale of a pilot car and a plurality of trailers.

60

In carrying out my invention I prefer to provide a plurality of posts 1, provided with base members 2 for the track frame at the top thereof, the base members 2 having up-standing bracket arms 3 and 4. The number of posts and bracket arms will depend upon the number required to maintain the aerial rails or wires 5 comparatively taut, the rails or wires 5 being fastened to the upper ends of the bracket arms 3 and 4 in any well known manner.

65

The bracket arms at the stations where trailers are to be detached are preferably connected with yielding or spring braking strips 6, adapted to bear against wear plates or braking strips on the trailers, as will be explained hereinafter. The posts 1 at the stations have upwardly extending and laterally curved trip arms 7, the curved portions 8 of which come in contact with the pivoted levers on the setting mechanism of the trailers, to be presently described.

75

It is apparent that the posts will be arranged in parallel so that there will be parallel rails 5 to support the pilot car and trailers on opposite sides, as clearly shown in Fig. 1.

80

The pilot car may consist of a rectangular hollow member 9, having overhanging edges 10, beneath which are traction wheels 11 on opposite sides of the car on shafts 12 and 13. The shafts 12 and 13 extend through the side walls of the car to support the traction wheels or pulleys on the ends thereof and which wheels or pulleys ride on the rails 5—5.

90

The forward grooved traction wheels 11 on shaft 13 are idlers while those on the shaft 12 are driven through a gearing from a motor 14. The motor 14 may be an electric motor if desired and may be energized either by a trolley or through a storage battery 15. The gear 16 on the motor drives a gear 17 on a shaft 18, which, in turn, carries a pinion 19, meshing with the gear 20 on shaft 12 so that shaft 12 will be positively

100

105

driven. Therefore, when the motor 14 is cut in the circuit and receives its energy, the pilot car or motor car will be driven over the track formed by the rails 5-5. 5 Access may be had to the interior of the car 9 by the hinged door 21.

On the forward end of the motor car is a bumper 22, corresponding to the bumper 23 on a trailer 24, the bumper having a shock 10 transmitting member 24', pressed out by a spring 25, as will be seen by reference to Fig. 2.

Projecting from the rear of the pilot car 9 are two parallel arms 26, between which 15 is pivoted a coupling hook or member 27, adapted to engage one of the bars 28 of a squirrel cage complementary coupling member 29, mounted in bearings in the frame 30 and having a ratchet 31 rigid therewith. 20 The frame 30 carries an elbow-shaped ratchet consisting of a pawl 32 and an up-standing arm 32'. The pawl 32 engages in the teeth of the ratchet 31 and the arm 32' is adapted to be tripped by a pin or pro- 25 jection 33 on the wheel 34, mounted on the shaft 35 in the frame 30. The toothed wheel 34 is loose on shaft 35 and it can be disengaged from the shaft through the medium of the pawl 36 and ratchet 37 so that the 30 pin 33 will have any predetermined relative position with respect to the arm 32'.

The wheel 34 is provided with a coil spring 38, which will restore it to its normal position each time it is swung in a rotative 35 movement to bring the pin 33 into contact with the arm 32'. The swinging movement is effected by a yielding lever 39, mounted in frame 30 and having a dog 40 to engage with the teeth 41 on the wheel 34. The nor- 40 mal upright position of the lever 39 is maintained by a yielding flat spring 42, so that the upper end 43 of the lever 39 will normally be in a vertical position through the slot 44.

45 If the pilot car is to pass from the central station to a plurality of substations or delivery stations, the train, consisting of as many trailers as there are stations to receive mail, will be started over the track. 50 When the train passes the first station for which the setting mechanism in the trailer has been set, the upstanding portion 43 of the lever 39 will strike against the curved portion 8 of the arm 7. At the same time 55 the wear plate or braking surface 45 will contact with the spring strip 6. The lever 39 will be thrown rearwardly so as to rotate the wheel 34 the required distance, for example, one notch. Since the wheel 34 in the 60 first car, which will be the last car in the train, will have its pin 33 set near to the arm 32', said pin will come into contact with arm 32', throwing the pawl 32 out of engagement with the ratchet 31 so that the 65 squirrel cage coupling member 28 will be

free to rotate on its journals, thereby releasing the coupling member 27 and permitting the rest of the trailers if there are a number of them, or the pilot car in case there is only one trailer, to proceed.

If there are a number of trailers in the train, each successive arm 43 will come in contact with the curved portion 8 of the arm 7 but the second trailer, which, of course, will then be the last car in the train, 75 will be set so that two divisions or two throws of the wheel 34 must be made before the pin 33 will contact with 32'. The releasing mechanism in the third car, then the last car, will be set so that three throws of 80 the wheel 34 must take place before the car can be released and so on up to the total number of cars.

The pilot car or motor car may have a bumper 22 to strike against any empty 85 which is ahead of it so that it will push the empty along the track to return it to the central station and if desired, the front of the pilot car may have a squirrel cage coupling member 28, corresponding to the 90 one on the front of the trailer except it will remain stationary so that it may engage with a complementary coupling member 27 on the car which it is pushing and thereby couple up the cars on the front of the pilot 95 car as well as the rear.

It will be apparent that when the train initially starts out, it will automatically proceed under its own power until it comes to the first station, where it will drop a car. Then it will proceed to the second station, where it will drop the second car, etc., until all of the cars in the train have been dropped. The consignee may then remove 100 the mail matter or other material in the car, leaving it on the track.

After the pilot car has made the circuit, it may start out with a new train, having the selected mechanisms in the trailers set for their particular stations. On the second 110 round, the train will drop the first car which, of course, will be the last one in the train, and pick up the previously dropped car at that station. When the train reaches the second station, the second car then the 115 last one in the train, will be dropped and another empty will be picked up in front of the train, the train proceeding until all of the loaded cars have been dropped at their respective stations and empties returned by the pilot car, which finally will be the last car in the train.

Of course, it is to be understood that the trailers are supported on the trolley, tracks or rails by idler wheels 46.

It will be apparent that the device is entirely automatic and that the cars may be successively dropped and empties picked up while the pilot car is making the circuit covered by its tracks.

My invention particularly lends itself for use for mail delivery but obviously it may also be designed for carrying merchandise if desired.

5. What I claim and desire to secure by Letters Patent is:

1. In an aerial railway system, an aerial track, a pilot car movable over the track, a trailer having a squirrel cage coupling member, a complementary coupling member on the pilot car engaging one of the longitudinal bars of the squirrel cage coupling member, a pawl normally holding the squirrel cage coupling member against rotation, and 10 means for releasing the pawl from engagement with the squirrel cage member to permit the cars to become uncoupled.

2. In an aerial railway system, a pilot car, means for operating it, an aerial railway 20 over which the car moves, a trailer, a rotatable coupling member on the trailer, a pivoted hook coupling member on the pilot car engaging the rotatable coupling member, means for normally holding the rotatable 25 member against rotation, whereby the two cars will be coupled, and means for releasing said first named means to permit the rotatable coupling member to rotate the outer coupling engagement with the hook.

3. In an aerial railway system, a pilot car, means for operating it, an aerial railway over which the car moves, a trailer, a rotatable coupling member on the trailer, a pivoted hook coupling member on the pilot car 35 engaging the rotatable coupling member, means for normally holding the rotatable member against rotation, whereby the two cars will be coupled, means for releasing said first named means to permit the rotatable 40 coupling member to rotate the outer coupling engagement with the hook, said means comprising an upstanding lever projecting through the top of the trailer and adapted to contact with the tripping arm above the 45 track, and a ratchet actuated pin controlled

by said arm and movable into engagement with said first mentioned means.

4. In an aerial railway, a track, a pilot car movable over said track, a trailer adapted to be connected to the pilot car, a coupling for effecting the connection comprising a hook member on the pilot car, a rotatable coupling member of squirrel cage form in the trailer to be engaged by the hook shaped member, an elbow shaped dog having a pawl 50 to engage with the ratchet on the rotatable coupling member and provided with an upstanding arm, a rotatable ratchet wheel having a pin movable into engagement with the upstanding arm to throw the pawl out of engagement with the ratchet wheel, an arm for actuating said wheel, said arm extending through the roof of the trailer, and an obstruction in the path of movement of the arm whereby said arm may be swung into 55 functional position.

5. In an aerial railway, a track, a pilot car movable over said track, a trailer adapted to be connected to the pilot car, a coupling for effecting the connection comprising a hook member on the pilot car, a rotatable coupling member of squirrel cage form in the trailer to be engaged by the hook shaped member, an elbow shaped dog having 60 a pawl to engage with the ratchet on the rotatable coupling member and provided with an upstanding arm, a rotatable ratchet wheel having a pin movable into engagement with the upstanding arm to throw the pawl out of engagement with the ratchet wheel, an arm 65 for actuating said wheel, said arm extending through the roof of the trailer, an obstruction in the path of movement of the arm whereby said arm may be swung into functional position, 70 and a spring for restoring the arm to normal position after it has functioned.

In testimony whereof I affix my signature.

HENRY W. ANTHOLZ.
